COVER TUCKING AND BOOK EJECTING
MECHANISM FOR MATCH BOOKING MA-
CHINESCharles F. Wright, Akron, Ohio, assignor to The
Diamond Match Company, New York, N. Y., a
corporation of Delaware

Application May 4, 1939, Serial No. 271,740

3 Claims. (Cl. 93—2)

This invention relates to match booking machines, having reference especially to cover-flap tucking or fastening mechanism and to means for delivering the assembled book elements to and discharging them from the effective path of the tucking or fastening mechanism. A match-booking machine of the type referred to is illustrated in Patent No. 1,042,472 dated October 29, 1912.

10 An object of my invention is to improve the flap tucking effect by the provision of means whereby a smooth and uniform compound motion of the tucker devices is ensured while the machine is running at high speed.

15 Another object is to provide simple and efficient means whereby the open books are uniformly positioned and held in the tucking or fastening zone, and whereby the completed books are positively discharged coincidentally with the 20 advancement of succeeding book elements to the tucking or fastening zone.

With these objects in view my invention comprises novel features of construction and combinations of parts which in a preferred form will 25 be hereinafter described, and the scope of the invention then expressed in the appended claims.

In the drawings—

Figure 1 is an elevation, partly in section, of a portion of the delivery end of a match booking machine equipped with flap tucking mechanism embodying my invention, a part of the frame being broken away for clearness, and a part of 30 an adjacent stacker being shown.

Fig. 2 is a rear elevation of the mechanism shown in Fig. 1, the stacker being omitted.

Fig. 3 is a transverse vertical section through the intermittently-rotatable flap folding wheel and the adjacent book ejecting and flap tucking devices, as on the line 3—3 of Fig. 2; the receiving end of the stacker being indicated.

Fig. 4 is a horizontal section, as on the line 4—4 of Fig. 3.

Fig. 5 is a perspective view of the reciprocative lifter arm of the tucker mechanism, and its actuating cam.

Fig. 6 is a similar view of the book holding and ejecting lever and its actuating cams.

Referring to the drawings, 10 designates a portion of the main frame at the delivery end of a 50 match booking machine of the type referred to, and 11 designates the main cam shaft which extends longitudinally of the machine. 12 designates an intermittently-movable chain of book holders from which succeeding pairs of books with outwardly extending closure flaps are ejected

by means of a horizontally reciprocating plunger 13, which carrier and plunger are operated in timed relation through suitable connections with cams on the shaft 11.

14 designates an intermittently rotatable wheel 5 which is mounted on the frame adjacent the path of the book holders, and which wheel has in and around its periphery equally spaced pairs of pockets 15 into each succeeding pair of which, in a dwell of the wheel, the ejected books are inserted by the plunger 13 with the closure flaps of the books extending outwardly from the wheel. The wheel is actuated in the usual manner. Overlying the upper semi-circular path of the wheel are spaced flap-bending members 16 which 10 terminate in rearward resilient extensions 17 which overhang an adjacent channeled bed 18 supported by the main frame. The cover flaps of each succeeding pair of books in their intermittent travel to the extensions are angularly 15 flexed and then, while the wheel is at rest, the books are endwise ejected from the pockets of the wheel and upon the bed 18 by novel mechanism hereinafter described. This mechanism advances the books beneath the extensions 17 in 20 a manner to effect the folding of the respective flaps flatwise upon the contained matches, the extensions yieldingly pressing upon and holding down the folded flaps. The books are discharged in pairs from the wheel 14 in similar endwise 25 and face arrangement, the larger or headed ends of the matches leading and the fold flaps of the covers being upward.

A reciprocative tucker arm 19 overhangs the wheel, which arm has a downwardly extending 35 bifurcated portion 20 terminating in friction heads 21 in proximity to the flaps of the match books which are imposed on the bed. The heads 21, by actuation of the tucker arm, are effective to insert the free ends of the cover flaps (a) of 40 each succeeding pair of books (B) under the retaining folds (c) of the covers at the narrow ends of the respective books.

The forward end of the tucker arm is pivoted to the upstanding arm 22 of a lever which is fulcrumed on a stud 220 on the supporting frame of the booking machine. The inclined depending arm 23 of the lever has a roll 24 which is fitted in the race of a face cam 25 fast on the main shaft 11 of the machine, the contour of the cam 50 race being such that at a determined interval in each rotation of the cam the lever is oscillated to effect horizontal reciprocation of the tucker arm, as set forth in Patent No. 1,042,472 aforesaid.

In the machine of the patent the vertical mo- 55

tion of the reciprocating tucker arm in respect to the cover flaps is effected by means of a series of cross-rods equally spaced around the periphery of the intermittently rotatable flap folding wheel, 5 each of which rods in the intermittent progress of the wheel co-acts with a cam projecting on the under side of the arm in a manner to raise the arm and thus hold it when the wheel is at rest. Then in the succeeding initial movement of the 10 wheel the rod escapes the stud and permits the descent of the arm by gravity. When the machine is run at high speed the rapid recurrent action of the succeeding rods on the cam projection of the tucker arm produces an irregular 15 chattering vibration of the arm with consequent impairment of the tucking effect.

To overcome this objection the present invention provides improved means for effecting a smooth and uniform vertical movement of the 20 reciprocating tucker arm, which means includes a lifter bar 26 having at its upper end a roll 27 upon which a suitably disposed insert 28 in the arm 19 is normally held by means of a spring connection 29 between the bar and arm. The 25 arm is provided on its under side with a depending guide block 30 which is loosely fitted in a circumferential groove 31 in the flap folding wheel. The bar 26 has a bifurcated foot 32 that straddles a shaft 33 having its bearings in a 30 suitably disposed bracket 34 on the frame structure 18, and in an upstanding bracket 340 on the base 35 of the structure. The shaft 33 is driven from the main shaft 11 by sprocket and chain connections, as 36. The foot of the bar 26 is 35 equipped with a lateral roll 31 which is operatively fitted in the continuous race of a face cam 38 fast on the shaft 33, the contour of the cam being such that the lifter is uniformly raised and lowered at determined intervals to effect the rising and permit the falling motion of the arm 19 relatively to the cover flaps of the match books supported on the bed 18.

In the embodiment of my invention herein illustrated the wheel 14 is in the form of a drum 45 having two spaced annular grooves 39 of substantial depth which medially intersect the pockets 15, and having also the intermediate groove 31 hereinbefore referred to adapted to receive and guide the vertically movable lifter bar 26 50 as well as the block 30 on the tucker arm 19. The bed 18 is provided with spaced slots 40 in line with the respective grooves 39, the floors of the channels of the bed being coplanar, or substantially so, with the floors of the respective 55 wheel pockets that are located adjacent the bed when the wheel is at rest. Mounted to swing in a path intersecting the bed-slots 40 and the respective wheel slots 39 adjacent thereto, are the upper portions of the respective arms 41 of the bifurcated upper end of a vertical lever 42 whereof the lower end is pivotally connected by means of a link 43 to a bracket 44 on the base of the main frame.

The upper end of each of the arms 41 provides an ejector head 440 having front and rear upstanding fingers 45 and 46, respectively, which are adapted by actuation of the lever in a vertical orbital or four-way path to embrace the adjacent book (B) contained in the pocket of the 65 wheel in proximity to the bed 18, then to withdraw the book and position it upon the bed directly beneath the overhanging tucker head and there hold the book (without liability of its slippage); until the cover flap has been acted upon 70 by the tucker head. Then the lever moves down-

ward to clear the bottom of the completed book and swings forward and up to embrace the next succeeding match book located in the wheel pocket in proximity to the bed. This completes the cycle of motion of the lever, at which stage 5 the finger 46 of the lever head is situated adjacent the forward narrow end of the book which is positioned on the bed, as seen in Fig. 3. In the next rearward movement of the lever, while a book is being removed from the wheel 10 and placed beneath the head, the completed book on the bed is directly and positively pushed rearward by the finger 46 of the lever head and beyond the tucking zone without the intervention of a succeeding book. 15

The means herein illustrated for actuating the lever 42 in timed relation to the pocketed wheel and the tucking devices is as follows:

The lower end of the lever 42 is provided with a roll 47 which runs in an open cam 48 formed 20 in the face of a gear 49 loose on a stud 50 which is supported by the upstanding bracket 340, such gear meshing with and being actuated by a gear 51 fast on the driven shaft 33 hereinbefore mentioned. The contour of the cam on 25 the gear 49 is such that in each rotation thereof a determined rising and falling motion is imparted to the lever 42. The lever is also equipped with a roll 52 which runs in a face cam 30 53 on the gear 51, the contour of which cam 30 is such that an oscillating movement is imparted to the lever during the rising and falling motion of the latter, the combined motions thus produced effecting the described vertical orbital or four-way motion of the lever. 35

In Figs. 1 and 3 of the drawings, I have indicated the receiving pocketed portion of a book stacker 54 in close relation to the bed so that as the ejector head shifts each opposing pair of completed books from the path of the tucker 40 devices, the head directly and positively pushes such books into the proximate pockets 55 of the stacker.

From the foregoing it will be seen that simple and efficient mechanism is provided whereby the books as they are successively ejected from the pocketed wheel are accurately positioned in the effective paths of the tucker heads and are there securely held while the flaps are being tucked. Also that the completed books are positively moved from the tucking zone and entered in the pockets of the stacker by the direct action of the book ejecting element instead of by the action of the succeeding books in their passage from the wheel to the tucking zone. 55

It is to be understood that my invention is not limited to the particular exemplifying form thereof herein disclosed, as the mechanism may be modified within the principle of the invention and the scope of the appended claims. 60

I claim—

1. The combination of means for supporting a match book having an open cover flap and a retaining portion for the free end of the flap, a flap tucking member overhanging said supporting means and movable relatively to the cover flap, a pivoted element carrying said member, means for reciprocating said element longitudinally of the cover flap, a vertically reciprocative lifter bar supporting said element, means for maintaining said element in contact with said lifter bar, and a cam for positively raising and lowering said bar in timed relation to its longitudinal travel, whereby a smooth and 75

uniform compound motion of the pivoted element and the tucking member is effected.

2. The combination of an intermittently-movable pocketed element for successively receiving match books and advancing them to a path of discharge, each book having an open cover flap and a retaining portion for the free end of the flap, a book support adjacent said path of discharge, means including a flap tucking member which overhangs said support, means including an ejector head movable in a vertical orbital path intersecting the plane of the book support and the adjacent pocket of said element, said ejector head constructed to embrace an overlying match book, and means for actuating said ejector head in timed relation to the pocketed element and the flap tucking member.

3. The combination of an intermittently-movable pocketed element for successively receiving match books and advancing them to a path of discharge, a book support adjacent said path of discharge, means comprising a pivotally mounted lever having a head with upstanding fingers thereon spaced to embrace a match book from its underside, book cover fastening means overhanging said support, and means for actuating said lever to move the head thereof and its fingers in a vertical orbital path intersecting the plane of the book support and the adjacent pocket of said element. 5 10
